UNITED STATES PATENT OFFICE.

CHARLES F. CROMMETT, OF CHELSEA, MASSACHUSETTS.

VALVE.

1,353,321.

Specification of Letters Patent. Patented Sept. 21, 1920.

Application filed July 25, 1916. Serial No. 111,283.

To all whom it may concern:

Be it known that I, CHARLES F. CROMMETT, a citizen of the United States, and a resident of Chelsea, county of Suffolk, and State of Massachusetts, have invented an Improvement in Valves, of which the following description, in connection with the accompanying drawings, is a specification, like characters on the drawings representing like parts.

The specific illustrative embodiment of my invention here shown and described is a valve suitable for use as an outlet for gas or fluid held under pressure, and is an improvement upon the type of valve shown and described in my application, Serial No. 100,121, filed May 26, 1916.

In the drawings:

Figure 1 is a side elevation showing the valve protector and indicating the general position of the valve;

Fig. 2 is a cross section taken on the line 2—2 of Fig. 1; and

Figs. 3 and 4 show modifications.

One of the objects of my invention is to provide a valve whereby the entrance of atmospheric air into a gas container may be prevented and the exhausted container upon being returned to its filling station may be immediately refilled without the necessity of being first pumped out to empty it of air which without the use of such a device as mine would have passed into it following the exhaustion of the gas or fluid it originally contained. A further object of the present embodiment of my invention is so to construct said valve that the user cannot tamper with or prevent its operation.

I have shown the main valve body 1 screwed into the top of a gas or fluid-container 2 and covered by a protecting cap 3 arranged to screw upon the neck 4 and provided at the top with a nut 5 to make it easily removable.

Upon the top of the valve body is screwed the usual nut 6 for retaining the packing 7. Through the center of the nut 6 fits the valve shank 8 which is provided at its upper end with a squared portion 9 to permit its being turned by a wrench. The upper part of the valve shank 8 is smooth, but near its lower end it is provided with threads which fit corresponding threads in the bore of the valve body. Below the threads the valve shank is tapered as at 10 to make a

tight closure against the shoulder 11 in the valve bore.

The lower end of the valve shank 8 is bored and threaded to receive the threaded extension of the plug 12, said extension being threaded oppositely to the threads upon the exterior of the valve shank 8. The plug 12 has projecting from its lower end the squared portion 13 which engages a similarly shaped opening 14 in the insert

15 which so fits into the valve body 1 as to be non-rotatable relatively thereto. In this manner the plug 12 is prevented from rotating, but upon the turning of the valve shank 8 it will advance or recede in accordance respectively with the downward and upward movement of the main valve shank 8.

The main outlet nozzle of the valve projects laterally from the side of the valve body 1 and is indicated at 16. In this nozzle is slidably located the ring 17 which is normally kept in its outermost position by the spring 18. Conically shaped to fit the opening of the ring 17 is the plunger 19 which is slidably mounted in the plug 20 and normally kept in close fitting contact with said opening by means of the spring 21 which abuts against the locking plug 22.

Through the locking plug 22 and the plug 20 may be bored vents 23 to permit the egress of the gas which when the main valves 8 and 12 are open flows from the container 2 through the tube 24 and bypass 25 past conical portions 10 and 12 of the main valve mechanism, through the tube 26 and central opening of the ring 17, depressing the spring-pressed plug 19 and flowing on and out through the tubes 23. The pressure of the spring 21 may be at approximately 2 lbs. (or any other desired pressure) so that it will be impossible for the pressure of the gas within the container to be reduced below the pressure of said spring, which will return the plug 19 to its seat when that pressure is reached and prevent any atmospheric air entering the container.

In Figs. 3 and 4 I have shown modifications of my valve. In Fig. 3 the main valve is headed as shown at 27, said head being pocketed within the shank 8 in such a way that the rotation of said shank will lift the valve away from its seat.

As a continuation of the main valve a sleeve 28 is provided within which is a

spring 29 which is adapted to press the plug 30 into the upper end of the aperture of the tube 31 at any desired pressure (say 2 lbs.), thus preventing any atmospheric air from entering the container after the gas has been reduced to that pressure. A by-pass 32 is provided and within it the spring-operated plug 33 is held in a closed position at a somewhat greater pressure than the spring 29.

In using this modification the gas, when the main valve mechanism has been opened, escapes through the tube 24 and lifting the plug 30 passes around it and out through the tube 34 until the pressure is reduced to a point equal to the strength of the spring 29 whereupon the plug 30 advances and prevents further gas escape. In refilling the container the gas is forced in through the tube 34 past the sleeve 28 into the by-pass 32, and forcing back the plug 33 passes into the container through the lower end of the by-pass 32.

In Fig. 4 the principle of operation is very similar to that of the construction shown in Fig. 2, the main valve apparatus being constructed, however, like that shown in Fig. 3, except that a conical seat 35 is provided upon which the lower end of the valve seats.

In Figs 2 and 4 the collar 17 is prevented from moving out of its socket by the ring 36.

In using the ordinary valve attached to containers holding gas or fluid under pressure, the user can permit the tank to become empty until its interior pressure is equal to the pressure of the atmosphere outside, with the result that air leaks into the tank through the valve opening. This results in the necessity for pumping out of the used containers before refilling them, the mixture of gas or fluid and air still remaining therein. This entails not only a waste of gas or

fluid but also a considerable waste of time and power. By using my device, however, such waste is obviated.

While I have described several specific embodiments of my invention I do not wish to be limited to the particular construction shown nor to the particular use designated, and many modifications of my invention may obviously be resorted to without departing from the spirit or scope thereof.

I claim:

1. In combination with a container for compressed gases, a main valve manually operable to open and close a passage between the interior of the container and the exterior thereof, valve means operatively interposed in said passage for automatically opposing the egress of gas through said passage below a predetermined pressure thereby to prevent complete emptying of said container and the flow of air therein from the outside atmosphere, and automatically openable by gas pressure in a charging direction to permit recharging of said container.

2. In a gas or fluid-controlling valve, main valve means and auxiliary valve means comprising an auxiliary valve and a seat therefor, said valve and seat being resiliently pressed together, one being movable in one direction by pressure in one direction and the other being movable in the opposite direction by pressure in another direction, and limiting means opposing movement of both said valve and seat beyond predetermined points, whereby either pressure-actuated movement of said valve or pressure-actuated movement of said seat may effect separation of valve and seat.

In testimony whereof I have signed my name to this specification.

CHARLES F. CROMMETT.
